UNITED STATES PATENT OFFICE.

ONUFRE WERESIUK, OF NEW CASTLE, PENNSYLVANIA.

CURTAIN AND SHADE BRACKET.

Application filed November 18, 1924. Serial No. 750,563.

This invention relates to new and useful improvements in curtain and shade brackets, and is primarily designed to be attached to a window frame without objectionable defacing or marring thereof.

The primary object of the invention is to provide a bracket of the above mentioned type which may be easily and quickly placed in practical use and may be cheaply manufactured.

Other objects of the invention will be apparent during the course of the following description.

In the accompanying drawings forming a part of the specification and in which like numerals are employed to designate like parts throughout the same,

Figure 1 is a vertical sectional view of a window frame equipped with a curtain and shade bracket embodying this invention,

Figure 2 is a fragmentary front elevational view of a window frame equipped with the curtain and shade bracket shown in Fig. 1,

Figure 3 is a fragmentary elevational view, partly broken away, of a window frame equipped with a pair of curtain and shade brackets of a modified form,

Figure 4 is a fragmentary top plan view of a window frame equipped with the type of curtain and shade bracket shown in Fig. 3,

Figure 5 is a detail elevational view of the type of curtain and shade bracket shown in Figs. 3 and 4,

Figure 6 is a fragmentary edge elevational view of a window frame equipped with a further modified form of curtain and shade bracket,

Figure 7 is a top plan view of the curtain and shade bracket shown in Fig. 6,

Figure 8 is a front elevational view of a further modified form of bracket adapted to be removably attached to a window frame,

Figure 9 illustrates in detail perspective the portion of the curtain and shade bracket shown in Fig. 8 employed for attaching the bracket to a window frame,

Figure 10 is a top plan view of a fragmentary portion of a window frame having the curtain and shade bracket shown in Fig. 8 attached thereto,

Figure 11 illustrates a modified form of attaching means for a curtain and shade

bracket of the general type illustrated in Figs. 8 and 10,

Figure 12 is a fragmentary front elevational view of a further modified form of curtain and shade bracket,

Figure 13 is a detail elevational view of a modified form of attaching spur, and

Figure 14 illustrates in side elevation a shade pintle receiving bracket demountably connected to a supporting plate.

Referring more in detail to the several views and particularly Figs. 1 and 2, the reference numeral 5 designates a fragmentary portion of a window frame having the upper and lower flanges 6 and 7 respectively.

The S-shaped curtain and shade bracket 8 is adapted to be connected to this window frame, between the flanges 6 and 7, without the use of any screws or the like which would deface or mar the said frame. This

bracket 8 is provided with a rigid spur 9 which is intended to engage the edge flange 7 and to be embedded therein by movement of the angle spur 10 freely received within the apertured lugs 11, 12 and 13 formed in the rear side of the bracket 8. The spur 10 is threaded at 10^a for the reception of a wing nut 14, the proper rotation of which will cause longitudinal movement of the spur 10 in the opposite direction to the spur 9 for securely fastening the bracket 8 to the frame 5. The bracket 8 has an enlargement 8^a formed at its upper end for holding a curtain pole 15 in the manner illustrated in Fig. 1. The bracket is further provided with shade pintle receiving sockets 16 and 17 for supporting the shade 18, shown in Fig. 2.

In the form of the invention shown in Figs. 3 to 5 inclusive, the bracket 19 has formed at its lower portion the spurs 20 which are adapted for being embedded in the lower flange 7 of the window frame 5.

The bracket 19 carries the apertured lugs 21 and 22 within the apertures of which is positioned the spur 23. This spur is threaded at 24 for engagement with the wing nut 25 which may be rotated upon the spur for causing the same to force against the lug 22 for causing the upper end of the spur 23, with the spurs 20 to be embedded in the flanges 6 and 7 respectively of the window frame.

Each bracket 19 has formed thereon the laterally projecting ears 26 having exten-

110

sions 27. These ears are intended for receiving the extension curtain poles 28 and the shade pintle receiving arm 29, as best illustrated in Figs. 3 and 4.

5 In the form of the invention shown in Figs. 6 and 7, the S-shaped bracket 30 is provided with an angular shoulder 31 adapted for resting against the upper outer edge of the window frame 5^a and to be held 10 thereagainst by the spur 32 which is loosely received in bearings 33 and 34 carried by the bracket and is to be tightened or drawn toward the shoulder 31 by the wing nut 35 which is threaded upon the outer end 36 15 of the spur 32 and bears against the bearing 34. This S-shaped bracket 30 is provided with an upwardly hooked extension 30^a having a shade pintle receiving socket 37 formed in the outer end thereof. The bracket 30 is 20 further provided with pintle sockets 38 and 39 and an enlargement 40 for holding in place a curtain pole, similar to the structure described in connection with Figs. 1 and 2.

In Figs. 8 to 10 inclusive there is shown 25 a further modified form of curtain and shade bracket which is designated by the reference numeral 41. The upper end of this bracket 41 is formed with an apertured ear 42 adapted to be received between the spaced fingers 30 43 of a lug 44 having an aperture 45 formed therein. A spur 46, similar to the spur 32 shown in Fig. 6, is to be received within the apertures in the ear 42 and lug 44 and carries a wing nut 47 for drawing the lug and ear toward the front face of the window frame 5^a, see Fig. 10. This bracket 41 is 35 further provided with struck-up ears 48 having extensions 49 at the upper ends thereof for connecting extension curtain poles and 40 shade roller pintle supporting arms similar to those illustrated in Figs. 3 and 4.

In Fig. 11 there is shown the upper end portion of a bracket 50 which is formed of sheet metal and has an inverted U-shaped 45 flange 51 projecting laterally therefrom. This bracket is apertured at 52 for the reception of a spur 53 by means of which the bracket 51 may be attached to a window frame similar to the frame 5^a shown in Figs. 50 6 and 10.

The bracket 54 shown in Fig. 12 is provided with a series of apertures 55 adapted for receiving a spur similar to the spur 53 shown in Fig. 11, by means of which the

bracket 54 may be attached to a window 55 frame of the type shown in Figs. 6, 7 and 10.

In Fig. 13, there is shown a pair of spurs 56 which are adjustably connected by the turn buckle 57 by means of which the outer ends of the spurs 56 may be drawn toward 60 or forced away from each other. These spurs 56 may be used in combination with the S-shaped bracket 8 shown in Figs. 1 and 2.

In Fig. 14 there is shown a bracket 58 65 having an ear 59 projecting laterally therefrom which is provided with an extension 60. The shade roller pintle receiving arm 61 is shown connected to this gear 59 and extension 60 by means of the apertured, U- 70 shaped base 62.

It is now believed that the method of constructing and the manner of operating the various types of curtain and shade brackets shown herein will be understood from the 75 above detail description of the same. It is to be understood that the forms of this invention herewith shown and described are to be taken as preferred examples of the same, and that various changes in the shape, 80 size, and arrangement of parts may be resorted to without departing from the spirit of the invention or the scope of the subjoined claims.

Having thus described the invention, 1 85 claim:

1. In a device of the type described, a curtain and a shade bracket having a ledge, a spur depending from the bracket, a second spur loosely carried by said bracket and projecting upwardly therefrom, and a wing nut 90 threaded on the second spur and bearing against said bracket ledge for moving the second spur away from the rigid spur to cause said spurs to be embedded in a window frame.

2. In a device of the type described, a curtain and shade bracket, a spur rigid therewith, a plurality of bearings carried by said bracket, a second spur loosely carried 100 by said bearings, and a wing nut threaded on the second spur and forcing against one of said bearings for moving the second spur away from the rigid spur to secure the bracket to a window frame.

In testimony whereof I affix my signature.

ONUFRE WERESIUK.
